UNITED STATES PATENT OFFICE.

WILLIAM R. THURSTON, OF HAMMOND, INDIANA.

LOCOMOTIVE ACETYLENE-GAS HEADLIGHT.

1,089,605.

Specification of Letters Patent. Patented Mar. 10, 1914.

Application filed September 13, 1912. Serial No. 720,207.

To all whom it may concern:

Be it known that I, WILLIAM R. THURSTON, a citizen of the United States, residing at Hammond, in the county of Lake and 5 State of Indiana, have invented a new and useful Locomotive Acetylene-Gas Headlight, of which the following is a specification.

The device forming the subject matter of 10 this application is a headlight adapted to be employed upon locomotive engines or wherever a brilliant illumination is required.

The device herein disclosed employs acetylene as an illuminant, and means is provided for receiving and moistening the carbid.

The invention aims to provide means for heating the interior of the water tank, to prevent freezing of the contents thereof.

20 Another object of the invention is to provide a movable shield for directing heated air from the burner into the pipe which enters the water tank.

Another object of the invention is to improve generally and to increase the utility of, devices of that type to which the present invention appertains.

With the above and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings, Figure 1 shows the invention in front elevation, parts being 40 broken away; Fig. 2 is a vertical longitudinal section through the water reservoir and attendant parts; Fig. 3 is a side elevation of the complete structure, parts being broken away; Fig. 4 is a vertical longitudinal section of the carbid receptacle and of the water reservoir, together with attendant parts; Fig. 5 is a transverse section on the line 5—5 of Fig. 2; Fig. 6 is a fragmental 45 top plan; Fig. 7 is a side elevation of the shield, the view depicting portions of the mechanism whereby the shield is manipulated, parts being broken away; Fig. 8 is a top plan of the shield.

In carrying out the invention there is provided a base 1, fixed to and upstanding from

which is a support 2, supporting a reflector 3 which preferably although not necessarily is of the common parabolic type.

The base 1 carries a supporting structure which may take the form of a plurality of 50 legs 4, connected with a funnel shaped gas chamber 5, the mouth of which is downwardly disposed. Threaded upon the mouth of the gas chamber 5 or otherwise secured thereto is a carbid receptacle 6. Threaded 55 to the smaller end of the gas chamber 5 is a lower water receptacle 8 which is of funnel shape, the mouth of the receptacle 8 being upwardly disposed, the threaded connection between the chamber 5 and the receptacle 8 60 being designated by the reference character 7. Threaded to the upper end of the lower water receptacle 8, as shown at 9, is a reservoir 10, the top 11 of which is provided with a nipple 12, receiving a cap 14, into which is 65 threaded a needle valve 15, provided at its outer end with a turning head 16; the pointed extremity of the needle valve 15 is received within a seat 17 formed at the axis of the lower water receptacle 8. Removably 70 mounted in the lower portion of the water receptacle 8 and disposed below the seat 17 is a retaining member 18, carrying a drip pipe 19, projecting into a distributing tube 20, the same being perforated, and being secured 75 at its lower end to the bottom of the carbid receptacle 6. Depending from the top 11 of the reservoir 10 is a foraminous strainer tube 21. Access is had to the interior of the strainer tube by means of a removable plug 22 which is mounted in the top 11 of the reservoir 10.

Extending from the gas chamber 5 is a delivery pipe 23, passing through an opening 23a into the interior of the reflector 3, the 80 free end of the pipe 23 carrying a burner 24 which may be of any desired type.

Communicating with the interior of the reflector 3 and extended rearwardly from the reflector is a funnel 25, communicating 85 with an upright pipe 26, the latter having a transverse extension 27 which communicates with a U-shaped circulating pipe 28, the latter being extended downwardly through the top 11 of the reservoir 10 into 90 the reservoir, the free end 29 of the circulating pipe 28 extending upwardly through the top 11.

Guides 30 in the form of rods are secured to the base 1, the guides 30 passing up- 95

wardly through the opening 23^a in the reflector 3. Mounted by means of brackets 31^a to slide on the guides 30 is a trough shaped shield 31 shown in Figs. 1, 8 and 7, and open at the back. A shaft 32 is journaled for rotation in bearings 32^a upon the base 1, the shaft 32 being provided with a forwardly extended finger 33 lying beneath the lower end of the shield 31. At one end of the shaft 32 there is an upstanding crank arm 34.

The operation of the device above described is as follows:—The carbid is placed within the receptacle 6, about the perforated tube 20, and, the plug 22 being removed, water is poured into the receptacle 8—10, the strainer tube 21 exercising its obvious function. When the needle valve 15 is rotated through the medium of the head 16, the point of the needle valve is retracted out of the seat 17, so that water may pass into the drip tube 19 and from the drip tube 19 into the distributing tube 20, the water passing through the perforations of the tube 20 and acting upon the carbid which is in the receptacle 6. The gas which is formed within the receptacle 6 will accumulate in the funnel shaped gas chamber 5, and pass thence, by way of the pipe 23 to the burner 24. To prevent an overheating of the reflector 3, the same is provided with ventilating apertures 35 which may be positioned at any desired points in the reflector. The heated air which is located within the contour of the reflector 3 will pass into the funnel 25 and thence by way of the upright pipe 26 and the extension 27, into the U-shaped circulating pipe 28, the air ultimately passing out of the free end 29 of the circulating pipe. Thus, the water which is in the reservoir 10 will be maintained at a temperature well above the freezing point.

Recalling that the device herein disclosed may be employed upon a locomotive engine, it will be understood that when desired the shield 31 may be manipulated from the cab of the engine by suitable mechanism (not shown) connected with the crank arm 34, motion being thus imparted to the shaft 32 and to the finger 33, the latter serving to

raise and to lower the shield 31 upon the guides 30.

The shield or screen 31 is a mere trough-shaped element, arched transversely away from the vertical axis of the burner 24. When the shield or screen 31 is raised, the same moves upwardly in front of the burner 24 but does not extinguish the flame. When the flame at the burner 24 is under full head and when the screen or shield 31 is depressed, sufficient heat will be generated to effect the desired result, even though the shield be lowered. When a light is not required, the flame at the burner 24 may be turned down to a considerable degree, under which circumstances the shield 31 may be raised, thereby directing the relatively small amount of heat generated directly into the funnel 25.

Having thus described the invention what is claimed is:—

1. In a device of the class described, a reflector; a burner within the contour of the reflector; a carbid receptacle and a water reservoir communicating with the carbid receptacle; means for admitting air to the reflector; and a combined ventilating and water heating pipe opening at one end through the reflector above the burner and at its other end provided with a return bend extended into the reservoir and having an open end discharging outside of the reservoir.

2. In a device of the class described, a reflector; a burner within the contour of the reflector; a carbid receptacle and a water reservoir communicating with the carbid receptacle; a pipe opening into the reflector above the burner and extended through the water receptacle; and a shield movable in front of the burner, the shield constituting means for directing heated air from the burner to the pipe.

In testimony that I claim the foregoing as my own, I have hereto affixed my signature in the presence of two witnesses.

WILLIAM R. THURSTON.
